(57) **CLAIM**

The ornamental design for an interbody fusion device, as shown and described.

DESCRIPTION

FIG. 1 is a rear perspective view of an interbody fusion device showing my new design;
FIG. 2 is a right-side elevation thereof;
FIG. 3 is a left-side elevation thereof;
FIG. 4 is a rear elevation thereof;
FIG. 5 is a front elevation thereof;
FIG. 6 is a top plan view thereof; and,
FIG. 7 is a bottom plan view thereof.
